UNITED STATES PATENT OFFICE

120,463

DESIGN FOR AN ELECTRICAL CONNECTING CAP

Louis Ludwig, Brooklyn, N. Y.

Application December 28, 1939, Serial No. 89,177

Term of patent 14 years

To all whom it may concern:

Be it known that I, Louis Ludwig, a citizen of the United States and a resident of Brooklyn, county of Kings, State of New York, have invented a new, original, and ornamental Design for an Electrical Connecting Cap, of which the following is a specification, reference being had to the accompanying drawing, forming part thereof, and in which:

Figure 1 is a top view of an electrical connecting cap showing my new design.

Figure 2 is a view of one end.

Figure 3 is a side view.

Figure 4 is a view of the other end.

Figure 5 is a bottom view.

I claim:

The ornamental design for an electrical connecting cap, as shown.

LOUIS LUDWIG.
